MODEL FORM GARMENT HANGER

Al Rosen, Brooklyn, N. Y.

Application January 14, 1948, Serial No. 2,275

6 Claims. (Cl. 223—68)

1

This invention relates to a garment hanger or support and more particularly to a two part device, resembling the human torso in configuration and being formed of plastic, for supporting clothing for display and storage purposes.

An object of the present invention is to provide a support for a garment, which support includes the imitation of the human shoulders and bust, or of the human shoulders alone, or of the bust alone, for supporting various appropriate garments, either for display purposes or storage, the device being formed of two parts, one of which has the shoulder portions and the other the bust portions, the two parts being laterally adjustable relative to each other.

A further object is to provide a device as aforesaid which is made of plastic and which is largely hollow.

Another object is to provide a device as aforesaid provided with means whereby either section may be hung, or either section may be supported from a base.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device constructed in accordance with this invention, in hanging position.

Fig. 2 is a perspective view of the shoulder portion of the device in hanging position.

Fig. 3 is a perspective view of the bust portion of the device in hanging position.

Fig. 4 is a side view of the device in supported position on a base.

Fig. 5 is a fragmentary view of a portion of Fig. 4 showing the adjustable connection employed.

Fig. 6 is a plan of Fig. 5.

Fig. 7 is a fragmentary view looking at the seam between the two sections, from the inside.

Fig. 8 is a section on the line 8—8 of Fig. 7.

Fig. 9 is a bottom view of Fig. 8 with the wing nut and washer removed.

The garment support 10, according to the present invention, comprises a shoulder section 11 and a bust section 12, both made of plastic and both largely hollow. The plastic is preferably transparent and clear and colorless. The two sections are detachable. They are joined along a seam 13 through the chest portion which

2

is depressed between the breasts 14 of the bust section 12 and which rises above each breast and extends to the arms 15 of the shoulder section 11. Section 11 thus has full shoulders 16 and these extend around the neck 17 to form the major portion of an annulus which is closed by an integral dome 18.

The bottom edge of section 11 at seam 13 and the top edge of section 12 at seam 13 have complementary rearwardly extending flanges 19 and 20 respectively. These are best shown in Fig. 7. In normal position, the flanges are exactly superposed, and are positioned by tongues 21 on flange 20 sliding in grooves 22 on flange 19, the tongues and grooves being at the outer end portions of the flanges. The flanges are also secured by three wing nut bolts 23, one at the center and one at each end portion. Each wing nut bolt has the usual bolt, nut and washer. The flange 19 has orifices 24 for the bolts, but the flange 20 has slots 25 therefor. The slots are substantially triangularly shaped, with their wide bases adjacent the inner edge of the flange and their narrow open ends 26 at the edge of the flange. Open end 26 is narrower than the diameter of the bolt 23, as is clearly shown in Fig. 9, so that the bolts 23 cannot be slid out of the slots 25 horizontally but the wing nuts must be removed and the bolts lifted vertically to separate the sections 11 and 12.

The flanges 19 and 20, which are curved in one plane, are flat in the other, so that they form means for sliding the sections 11 and 12 relative to each other, or more specifically, for sliding the section 12 rearward relative to the section 11 to push the breasts back of the front line of the shoulder section 11 so that the overall thickness of the garment support is reduced for storage. This sliding is permitted by the slots 25, the small open ends 26 of which assure that the sections will not become inadvertently separated. The tongue and groove connections and slots are in proper parallelism to permit the sliding.

The dome 18 is provided with a central hole 27 and a reinforcement 28 thereunder through which the hole 27 extends. A threaded hook 29 may be passed through this hole 27 and secured therein by a top nut 30 and a bottom wing nut 31. This hook may be employed for hanging the entire garment support as shown in Fig. 1, or for hanging the shoulder section only, as shown in Fig. 2, when the sections are separated. Furthermore, the hook can be placed through the center slot 25 of the section

12 for hanging this, as shown in Fig. 3 if desired.

The garment support is also provided with means for supporting it from a base 32, as shown in Fig. 4. This means includes a bracket 33 bolted to a boss 34 on the inner face of the section 11. The bracket includes two parallel spaced integral rings 35 against the outer edge of which rides a plate 36 having diverging wings 37 and against the inner edge of which rides a bridge plate 38 having flanges 40 overriding the side faces of the rings. A bolt 41 passing through the bridge and plate secure the two together and hold them in any adjusted position on the ring when the bolt is tightened, the bolt 41 having a nut 42 for this purpose. A bolt 43 passes through an orifice in one of the wings 37 into a plastic rod 44 which is secured to the base 32.

A similar means is attached to a boss 45 on the section 12. The rod 44 may support the entire device as shown in Fig. 4, or the top section 11 if the bottom section 12 is removed. If it is desired to support the bottom section alone, the bolt 43 is removed and placed in the corresponding hole of the means secured to the boss 45. No description of this second means is given since it is identical with the means described.

The angle of the garment hanger as a whole, or of either of the sections, when supported on the rod 44, can be quickly changed by merely loosening the nut 42, rotating the plate 36 about the rings 35 to the desired position, and thereafter tightening the nut 42.

The garment hanger may be hung by the hook in a closet to store a garment, either for long periods or short periods. If the garment does not require the bust portion to maintain its shape, section 12 may be removed. If the garment is such that it requires only the bust portion, section 11 is removed and the hook attached to section 12. If the garment support is used for display, for example of a blouse, it will probably be used as shown in Fig. 4. If the bust portion is not needed, section 12 can be removed. If it is to display an item such as brassière, section 11 can be removed and the rod 44 attached to section 12. If the device is to be stored, it can be removed from rod 44, or the hook removed if it has been hanging, and section 12 can be adjusted rearwardly relative to section 11 as aforesaid to move the foremost point of the breasts back to about the same point as the foremost point of section 11, thus conserving room.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a garment support having two superimposed sections open at their rear and shaped to conform to the upper portion of the female body and having horizontal meeting edges midway of the height thereof, a flange extended rearward from the bottom edge of the upper of the sections, a flange extended rearward from the top edge of the lower of the sections and engaging the flange of the upper section, interengaged means on said flanges for guiding forward and rearward movement of the sections relative to each other, said first flange being formed with spaced holes, said second flange being formed with triangularly

shaped slots aligned with said holes and with their wide bases at the inner edge of the flange and their narrower open ends at the outer edge of the flanges, bolts having threaded shanks extended through said holes and said slots, and nuts threaded onto the extended end of said shanks to be tightened against the adjacent flange for securing the sections in a desired shifted position relative to each other.

5 2. In a garment support having two superimposed sections open at their rear and shaped to conform to the upper portion of the female body and having horizontal meeting edges midway of the height thereof, a flange extended rearward from the bottom edge of the upper of the sections, a flange extended rearward from the top edge of the lower of the sections and engaging the flange of the upper section, interengaged means on said flanges for guiding forward and rearward movement of the sections relative to each other, said first flange being formed with spaced holes, said second flange being formed with triangularly shaped slots aligned with said holes and with their wide bases at the inner edge 10 of the flange and their narrower open ends at the outer edge of the flanges, bolts having threaded shanks extended through said holes and said slots, and nuts threaded onto the extended end of said shanks to be tightened against the adjacent flange for securing the sections in a desired shifted position relative to each other, said interengaged means comprising tongues formed on one of said flanges and extended toward the other flange, said other flange being formed with complementary grooves into which said tongues are slidably engaged, said tongues and said grooves being extended at right angles to said flanges.

20 3. In a garment support having two superimposed sections open at their rear and shaped to conform to the upper portion of the female body and having horizontal meeting edges midway of the height thereof, a flange extended rearward from the bottom edge of the upper of the sections, a flange extended rearward from the top edge of the lower of the sections and engaging the flange of the upper section, interengaged means on said flanges for guiding forward and rearward movement of the sections relative to each other, said first flange being formed with spaced holes, said second flange being formed with triangularly shaped slots aligned with said holes and with their wide bases at the inner edge 25 of the flange and their narrower open ends at the outer edges of the flanges, bolts having threaded shanks extended through said holes and said slots, and nuts threaded onto the extended end of said shanks to be tightened against the adjacent flange for securing the sections in a desired shifted position relative to each other, said open ends of said slots being narrower than the diameter of said bolts to retain said bolts against slipping out of the open ends of said slots.

30 4. In a garment support having two superimposed sections open at their rear and shaped to conform to the upper portion of the female body and having horizontal meeting edges midway of the height thereof, a flange extended rearward from the bottom edge of the upper of the sections, a flange extended rearward from the top edge of the lower of the sections and engaging the flange of the upper section, interengaged means on said flanges for guiding forward and rearward movement of the sections relative to each other, said first flange being formed with
